UNITED STATES PATENT OFFICE.

MORGAN W. DAVIES AND THOMAS J. THOMAS, OF OSWEGO, OREGON.

NEWSPAPER-WRAPPING MACHINE.

SPECIFICATION forming part of Letters Patent No. 541,318, dated June 18, 1895.

Application filed July 7, 1894. Serial No. 516,853. (No model.)

To all whom it may concern:

Be it known that we, MORGAN W. DAVIES and THOMAS J. THOMAS, citizens of the United States, residing at Oswego, in the county of 5 Clackamas and State of Oregon, have invented certain new and useful Improvements in Newspaper-Wrapping Machines; and we do hereby declare the following to be a full, clear, and exact description of the invention, 10 such as will enable others skilled in the art to which it appertains to make and use the same, reference being had to the accompanying drawings, and to the letters of reference marked thereon, which form a part of this 15 specification.

Our invention relates to improvements in newspaper wrapping and wrapper addressing machines, and the object of the invention is to provide a machine by which newspapers 20 can be automatically wrapped, the wrappers pasted and the address to which the paper is to be delivered printed on the wrapper.

With these ends in view our invention consists in the peculiar construction and arrangement of parts as will be hereinafter 25 fully pointed out and described.

In the accompanying drawings, Figure 1 is a side elevation, partly in section, of a machine embodying our improvements. Fig. 2 30 is a top plan view thereof. Fig. 3 is a vertical sectional view taken on a line at one side of the path of the vertically-reciprocating folder. Fig. 4 is a side elevation of the main frame of the machine. Figs. 5 to 10 are detail views, on a larger scale, illustrating the 35 various positions of the paper, wrapper, and parts acting thereon during the folding and wrapping operation. Fig. 11 is a detail view of the vertically-reciprocating folder. Fig. 40 11^a is a top view of the connection between this blade and the operating-lever. Figs. 12 and 13 are detail views of portions of the printing mechanism. Fig. 14 is a detail view showing in side elevation and plan one of 45 the plates preferably employed to guide the pasting-roller.

Like letters of reference denote corresponding parts in all the figures of the drawings, referring to which--

50 A designates the frame or body of the machine; and A² designates a shaft which is journaled in bearings on the frame A and is

designed to be connected by suitable belting or gearing with the drive wheel of any suitable motor or engine. On the shaft A², preferably near one end thereof and beyond the main frame is mounted to turn therewith a driving wheel or disk D. On the shaft A², between the sides of the frame A, is mounted a feed cylinder Y, in the surface of which 55 are formed two parallel annular grooves Y', into which extend rearwardly extending arms c of a feeding table or horizontal support T. The grooves Y' are of less depth than the thickness of the arms c of the feeding table so that the upper surface of said arms normally lies above the surface of the cylinder Y; and on said arms rests a roll of 60 wrapping paper E. The roll E is wound on a suitable core or support the ends of which 65 extend through vertical slots in standards or uprights E' on the frame A.

The central portion of the cylinder Y, between the grooves Y', which in the drawings is designated by the reference letter Z', is partially covered with a layer of leather or similar material Z'. As shown in Figs. 1 and 4 this layer Z' does not extend entirely around the cylinder but it is of such thickness that when during the revolution of the cylinder it 70 is brought between the arms c it projects above the upper surface thereof and bearing against the roll E serves to raise the same from said arms and by frictional contact said roll is revolved and a sheet of paper drawn 75 therefrom and forced forward over the table T. The paper is forced over the table T and below a shelf F supported above and lying parallel to said table. A knife or cutter t is arranged transversely across the machine, it being fitted in suitable guides on the frame A 80 below the feeding table, and said cutter is connected with mechanism to be hereinafter described by which after a sufficient amount of paper has been forced thereover to form a 85 newspaper wrapper it will be raised through a slot in the feeding table and sever the wrapper from the body of the sheet. The wrapper extends from the slot in the feeding table through which the cutter t operates over another slot or opening e'' in said table through 90 which type, arranged to print the desired address on the wrapper, are forced, by means described below.

To the table T, or the frame A, between the cutter slot *t*' therein and the type passage *e*'', is secured the lower end of an upright or standard S which has a vertical way or groove 5 formed therein. In said groove or way is fitted a block U to which is attached one end of a folding blade or arm *f* which blade extends transversely across the machine in line with a suitable passage in the feeding table. The 10 block U is connected in any suitable manner with the upper end of a rod M' the lower end of which is preferably threaded and extended through a passage formed in an inwardly projecting lug *m* on a vertically movable block 15 M extending through and adapted to move freely in a slot *h* formed in one of the legs or supports of the frame A. The block M is connected, by means of a pin and slot connection, with one end of a bell crank lever B which is 20 fulcrumed on a stud X supported from the main frame. To the other arm of this bell crank lever is attached an arm L on which is adjustably mounted a weight L' which acts to normally maintain the lever in the position 25 shown in Fig. 1 and keep the vertically reciprocating folding blade *f* in an elevated position.

In the rear arm of the lever B is formed a groove *k*' which opens at its ends through the 30 front face or side of the arm; and said groove is adapted to receive a pin *a* carried by a lug projecting from the wheel or disk D, so that as the driving wheel is revolved the lever B will be turned on its fulcrum and the forward 35 end thereof forced downwardly thus causing the folding blade *f* to pass through the slot in the table T.

A paste receptacle J is mounted on suitable ways or guides on the frame A, below and in 40 advance of the standard S, and said receptacle is connected by a rod or link K with the rear grooved arm of the bell crank lever, whereby as said lever is rocked or turned on its fulcrum the paste receptacle will be reciprocated horizontally. A portion of the rear end wall of 45 this receptacle is removed so that a portion of a paste distributing cylinder *l* therein is exposed. This cylinder *l* is mounted on a shaft journaled in the side walls of the receptacle J and one end of which projects beyond the 50 side of said receptacle. On the projecting portion of the said shaft is mounted a ratchet wheel; and on the same shaft is pivoted a small bell crank lever *k* one arm of which is 55 provided with a laterally projecting pin that extends into a slot formed in a bar *j*, which is pivoted at *i* to the frame A of the machine. To the other arm of the bell crank lever *k* is attached a pawl *m* which engages with the 60 teeth of the ratchet on the shaft of the paste distributing cylinder.

On the stud X, between the bell crank lever B and the frame A, is fulcrumed the lower end of a lever C. A link V connects this lever 65 with one end of a reciprocating bar W, which is arranged in suitable ways formed in the frame of the machine and to the forward end

of such bar is secured a folding blade *g*. In the lever C is formed a longitudinally extending groove B' which opens at its ends through 70 the forward face or side of said lever; and a pin *b* carried by the driving wheel D and projecting laterally therefrom on the opposite side from the pin *a*, is adapted to pass through such groove, as the wheel D revolves, and thus 75 operates to force forward the horizontally movable folding blade *g* and cause the same to force a newspaper and its wrapper between two parallel transverse extending rollers O P. (See Figs. 1 and 7.)

On one face the wheel D is provided with a cam surface D', which aids the return of the bell crank lever to the position shown in Fig. 1 and to maintain it in such position during a portion of the time that the horizontal blade 85 is moving. This blade and its operating lever are returned to their rearmost positions by a cam D² secured on, or cast integral with the driving wheel D, on the opposite face thereof from the cam D'. A rock shaft N', journaled 90 in suitable bearings on the frame of the machine, is provided near its ends with forwardly projecting fingers N² which extend below and support the head or bar to which the cutter *t* is secured. Said shaft is also provided at one 95 end with a rearwardly extending finger N. This finger extends or projects rearwardly into the path of the projecting pin *b* on the driving wheel, so that as said wheel revolves and the pin *b* thereon comes in contact with 100 the finger or arm N the shaft N' is rocked in its bearings and the cutter *t* is forced up through the slot *t*' in the table T and cuts from the sheet of paper that has been withdrawn from the roll E the amount necessary to form 105 a newspaper wrapper.

A lug *e* extending upwardly from the shaft N' has attached thereto the rear end of a bar or rod *d*, the forward end of such rod being enlarged to form a cam like head *d*' which 110 extends through a slot or passage in one of the bearings *b*'', of a shaft on which is secured a cylinder *b*' forming a part of the printing mechanism of our improved machine. The bearings of the shaft carrying said cylinder are fitted in suitable guide ways formed in depending arms *b*² on the main frame, so that said bearings are capable of a limited vertical movement. This printing mechanism consists essentially of an endless type 115 carrier passing around the printing cylinder *b*' and guiding and supporting wheels *f*' *g*', and an inking roller or cylinder *c*'.

The type carrier T' is preferably composed of a series of parallel transverse bars or plates 125 *e*', having suitable sockets to receive type, as shown in Fig. 13 of the drawings; and bands *m*' of leather or other similar material connecting said type bars. The lower ends or portions of the type bars *e*' are made substantially triangular or wedge shape in cross section, see Fig. 13, so as to take into the teeth of the wheels *f*' *g*', and printing cylinder *b*', so that as said cylinder is revolved, by 130

means to be hereinafter described, the type carrier will be advanced or fed along toward such cylinder one space or bar. A pawl h^2 is pivoted to an arm h' and engages with a 5 ratchet on the shaft of the printing cylinder b' so that as said cylinder is lifted, by means of the cam head d' on the bar or rod d , the pawl h^2 being in engagement with one of the teeth of the ratchet, said cylinder will be 10 turned one step and bring a new type bar e' into alignment with the opening e'' in the feeding table T.

The inking cylinder or roller c' is arranged between the supporting wheel g' and the 15 printing cylinder, and ink is applied thereto in any suitable and desirable manner. Such roller is preferably covered with a layer of felt or similar material and, as shown in Fig. 1, the faces of all the type in the type carrier 20 come in contact with such inked surface as said carrier is advanced toward the printing cylinder.

The paper and wrapper are, under the pressure of the vertically movable folder f forced 25 down into a passage f' formed in the machine and at the limit of the movement of the blade the paper and its wrapper are held firmly in position in the path of the horizontally reciprocating folder g between pivoted fingers 30 q and the front wall of the passage f' .

In arms or bars v , attached at one end to the sides of the paste receptacle J, is journaled a shaft carrying a pasting roller S' . The ends of the shaft on which said roller is 35 mounted project beyond the arms v and into guide ways n formed by the upper edges of plates n' secured to the inner faces of the sides of the main frame. These plates n' are of the form shown in Figs. 8, 9, 10, and 14. 40 By reference to these figures it will be seen that as the paste receptacle is moved forward, the roller S' will be first caused to travel forward and down an incline n^2 , thereby forcing a portion of the wrapper against the surface 45 of the paste distributing cylinder. See Fig. 8. The roller S' then travels in a substantially horizontal plane, as at n^3 , during which movement the paste covered portion of the wrapper is forced against the body thereof (see Fig. 9) 50 and the wrapping operation completed. The paper and its wrapper are prevented from forward movement during the time that the wrapper is being secured in place by a depending flange p , at the outer end of a forwardly projecting arm P' , which is secured 55 to the main frame, against which it is forced by the horizontally reciprocating folder g . As the paste receptacle continues to move forward the roller S' is drawn up a slight incline, at n^4 , and at the end of the movement of the receptacle J such roller has passed beyond the end of the arm P' and from below the wrapped paper thus allowing the latter to fall into a suitable receptacle placed below 60 the body of the machine.

In order that there will be no danger of the roller S' coming in contact with the exposed

surface of the paste distributing cylinder during its rearward movement, which would exist if such roller followed the same path traversed in its forward movement, we arrange above the upper edges of the plates n' pivotal plates n^5 . These plates, which are, as shown in Fig. 14, preferably pivoted to a lug on the adjacent plate n' , are so pivoted that their forward ends 70 normally lie flush with the surface of the upper edges of the plates n' beyond the inclined surfaces n^4 thereof. In its rearward movement the roller S' passes over the upper edges of these pivoted plates n^5 (as shown in Fig. 80 10) and reaches its upper rear position without contacting with the paste distributing cylinder.

The operation of our invention may be briefly stated as follows: As the shaft A^2 is 85 rotated the paper contained in the roll E is unwound and forced over the table T. The newspapers, folded as they leave the printing press, are fed on top of the wrapper below the shelf F. The wrapper and paper are fed forward on the feeding table until the wrapper extends across the printing aperture therein. As the pin b contacts with the rear end of the finger or arm N, on the rock shaft N', the cutter t is forced up through the aligned slot in 90 the table T at the same time that the printing wheel is raised and the type bar thereon which aligns with the aperture or slot e'' in the feeding table is forced therethrough and the address is printed on the wrapper. At this time 95 the pin a enters the groove k' in the bell crank lever and turning said lever on its fulcrum causes the vertically movable folding blade f to descend and fold the paper and wrapper, as in Figs. 5 and 6. As the pin a is leaving 100 the groove in the bell crank lever the pin b is in the groove in the lever C and such lever, through the link V, forces the bar W and horizontally movable blade g forward between the rollers O P. The newspaper and wrapper are thus folded again and forced forward 105 onto the top of the paste receptacle. As the blade g is withdrawn, by the action of the cam D^2 , and the blade f again begins to descend the paste receptacle is forced forward 110 by the rod K and the roller S' , as described, forces the overhanging or projecting portion of the wrapper first against the paste distributing cylinder and then against the body of the wrapper. When wrapped the paper is 115 dropped through the frame of the machine. As the blade f is moved upward the paste receptacle is withdrawn to receive thereon the next wrapper and paper as acted on by the blade g .

Having thus described our invention, what we claim as new, and desire to secure by Letters Patent, is—

1. In a newspaper wrapping machine, the combination with a supporting frame, a driving shaft journaled in said frame, of a feeding table mounted on the supporting frame terminating at one end in a pair of parallel arms adapted to support a roll of wrapping

paper, a feed cylinder secured on the driving shaft and having suitable grooves formed in its surface to receive the arms on the feeding table, and folding and pasting mechanisms connected with and adapted to be operated from the driving shaft, substantially as shown and described.

2. In a newspaper wrapping machine, the combination with a supporting frame, and a driving shaft journaled in said frame, of a feeding table mounted on the supporting frame and terminating at one end in a pair of parallel arms adapted to support a roll of wrapping paper, and a feed cylinder secured on the driving shaft and having suitable grooves formed in its surface to receive the arms on the feeding table and having its body, between the grooves therein, of such form as to project above the upper surfaces of the arms of the feeding table during a portion of each revolution, substantially as set forth.

3. In a newspaper wrapping machine, the combination with a supporting frame, and a driving shaft journaled in said frame, of slotted standards supported on the frame to form guides for the core of a roll of paper, a feeding table mounted on the supporting frame and having at one end a pair of arms adapted to support a roll of paper, and a feed cylinder secured on the driving shaft and having grooves formed in its surface to receive the arms of the feeding table and its body, between such grooves, partially covered by a layer of leather or similar material, of such thickness as to project above the surface of the arms of the table, substantially as set forth.

4. In a newspaper wrapping machine, the combination with a supporting frame, a driving shaft journaled in said frame and a feeding table mounted on the supporting frame, of a vertically movable folding blade adapted to pass through a slot in the feeding table, a bell crank lever fulcrumed on the supporting frame and having one end connected with the vertically movable folding blade and having a longitudinal groove formed in its other arm and opening at its ends through one face thereof, a wheel secured on the driving shaft and carrying a stud adapted to enter the groove in the bell crank lever as the shaft rotates, and a horizontally movable folding blade arranged below the feeding table and connected with the driving shaft so that it is reciprocated across the path of the vertically movable folding blade at each revolution of said shaft, substantially as shown and described.

5. In a newspaper wrapping machine, the combination with a supporting frame, a driving shaft journaled in said frame and a feeding table mounted on the supporting frame, of a vertically movable folding blade arranged to pass through a slot in the feeding table, a bell crank lever fulcrumed on the supporting frame and having one arm connected with the vertically movable folding blade and having

a longitudinal groove formed in its other arm and opening at its ends through one face thereof, a lever, C, fulcrumed on the supporting frame and having a longitudinal groove formed therein and opening at its ends through one face thereof, a horizontally movable folding blade arranged below the feeding table and connected with said lever, and a wheel secured on the driving shaft and provided with two laterally projecting pins adapted to enter the grooves in the levers by which the folding blades are reciprocated, substantially as shown and described.

6. In a newspaper wrapping machine, the combination with a supporting frame, a driving shaft journaled in said frame and a feeding table mounted on the supporting frame, of a vertically movable folding blade arranged to pass through a slot in the feeding table, a bell crank lever fulcrumed on the supporting frame and having a longitudinal groove formed in one of its arms and opening at its ends through one face thereof, connections between the other arm of said lever and the vertically movable folding blade, a lever, C, fulcrumed on the supporting frame having formed therein a longitudinal groove which opens at its ends through one face thereof, a bar fitted in suitable horizontal ways in the supporting frame and carrying a folding blade, a link connecting said bar with the lever, C, and a wheel secured on the driving shaft and provided with laterally projecting pins adapted to enter the grooves in the levers by which the folding blades are reciprocated, substantially as shown and described.

7. In a newspaper wrapping machine, the combination with a supporting frame, a driving shaft journaled in said frame and a feeding table mounted on the frame, of a vertically movable folding blade arranged to pass through a slot in the table, a bell crank lever fulcrumed on the supporting frame and having a longitudinal groove formed in one of its arms and opening at its ends through one face thereof, and its other arm connected with the vertically movable blade, a lever C fulcrumed on the supporting frame and having a longitudinal groove formed therein and opening at its ends through one face thereof, a horizontally movable folding blade arranged below the feeding table and connected with said lever, and a wheel secured on the driving shaft in a plane between the blade operating levers, and provided on opposite faces with laterally projecting pins adapted to enter the grooves in the blade operating levers, substantially as shown and described.

8. In a newspaper wrapping machine, the combination with a supporting frame, a driving shaft journaled in said frame, and a feeding table mounted on the frame, of a vertically movable folding blade arranged to pass through a slot in the feeding table, a bell crank lever fulcrumed on the supporting frame and having one arm connected with the vertically movable folding blade and having

a longitudinal groove formed in its other arm and opening at its ends through one face of said arm, a wheel secured on the driving shaft and provided with a pin adapted to enter the 5 groove in the bell crank lever and with a cam adapted to contact with the grooved arm of said lever during the time that said pin is out of the groove therein, a horizontally movable folding blade arranged below the feeding table, and connections between such blade and the driving shaft, substantially as shown and described.

9. In a newspaper wrapping machine, the combination with a supporting frame, a driving shaft journaled in said frame, a feeding table and a vertically movable folding blade, of a horizontally movable folding blade arranged to move across the path of the vertically movable blade, a lever fulcrumed on the 10 supporting frame and connected with the horizontally movable blade, and having formed therein a groove which opens at its ends through one face thereof, and a wheel secured on the driving shaft and provided with a laterally projecting pin, adapted to enter the groove in the blade operating lever, and with a cam adapted to contact with said lever when the pin aforesaid is not in engagement therewith, substantially as set forth.

10. In a newspaper wrapping machine, the combination with a supporting frame, a driving shaft journaled in the frame, and a feeding table supported on the frame, of a vertically movable folding blade arranged to pass 35 through a slot in the feeding table, a bell crank lever fulcrumed on the supporting frame and having one arm connected with the vertically movable blade, a weight adjustably connected to the other arm of said lever, a 40 lever C fulcrumed on the same center as the bell crank lever and having a longitudinal groove which opens at its ends through one face thereof, a horizontally movable folding blade connected with said lever, and a wheel 45 secured on the driving shaft, in a plane between the blade operating levers, and provided with laterally projecting pins, adapted to enter the groove in the lever C and a similar groove in the weighted arm of the bell 50 crank lever, and with cams D' D², substantially as shown and described, for the purpose specified.

11. In a newspaper wrapping machine, the combination with a supporting frame, a driving shaft journaled in said frame and a feeding table mounted on the frame, of a vertically movable folding blade adapted to pass through a slot in the feeding table, a bell crank lever fulcrumed on the supporting 55 frame and having formed in one arm a longitudinal groove which opens at its ends through one face of said arm, connections between the other arm of said lever and the vertically movable folding blade, a lever, C, fulcrumed on the supporting frame and having formed therein a longitudinal groove which opens at its ends through one face of said lever, a

horizontally movable folding blade arranged below the feeding table and connected with the lever, C, a cutter carried by one end of a 70 lever, fulcrumed on the supporting frame, and adapted to pass through a slot in the feeding table between the driving shaft and vertically movable folding blade, and a wheel secured on the driving shaft and provided 75 with laterally projecting pins, one of which is adapted to enter the groove in the bell crank lever while the other is adapted to enter the groove in the lever, C, and also contact with the free end of the lever carrying the 80 cutter at each revolution of the driving shaft, substantially as shown and described, for the purpose specified.

12. In a newspaper wrapping machine, the combination with a supporting frame, a driving shaft journaled in said frame and a feeding table mounted on the frame, of a vertically movable folding blade adapted to pass through a slot in the feeding table, a bell crank lever fulcrumed on the supporting 90 frame and having one end connected with the vertically movable folding blade, a paste receptacle mounted in ways in the supporting frame at one side of the path traversed by the vertically movable folding blade and connected with the other arm of the bell crank 95 lever, a paste distributing cylinder mounted within and having a portion of its surface projecting beyond said receptacle, a pasting roller journaled in arms attached to the paste 100 receptacle, a horizontally movable folding blade arranged above the paste receptacle to move across the path traversed by the vertically movable folding blade, connections between the horizontal movable blade and the 105 driving shaft, and means carried by said shaft for rocking the bell crank lever, substantially as shown and described, for the purpose specified.

13. In a newspaper wrapping machine, the combination with a supporting frame, a driving shaft journaled in said frame and a feeding table mounted on the frame, of folding mechanisms, substantially such as described, a reciprocating paste receptacle, a paste distributing cylinder mounted on a shaft journaled in opposite walls of the paste receptacle, a ratchet secured on said shaft at one side of the paste receptacle, a bell crank lever fulcrumed on said shaft and having one of its 110 arms provided with a pawl adapted to engage with said ratchet and its other arm provided with a laterally projecting pin which fits in a slot in a bar pivoted to the supporting frame, and a pasting roller journaled in arms attached to the paste receptacle, all combined and arranged in the manner shown and described, for the purpose specified.

14. In a newspaper wrapping machine, the combination with a supporting frame, a driving shaft journaled therein, two folding blades connected with and adapted to be reciprocated from the driving shaft through intersecting vertical and horizontal planes, a paste

receptacle mounted on the supporting frame below the path of the horizontally movable blade and parallel thereto, a paste distributing cylinder mounted on a shaft journaled in 5 the paste receptacle, guide plates attached to the frame on opposite sides of the path of the paste receptacle, a pasting roller carried by arms attached to the paste receptacle, the ends of the shaft of said roller extending beyond 10 the supporting bars and resting on the upper edges of the guide plates, and means for reciprocating the paste receptacle substantially as set forth.

15. In a newspaper wrapping machine, the combination with a supporting frame, a driving shaft, and a feeding table mounted on the frame, of a vertically movable folding blade arranged to pass through a slot in the feeding table, a horizontally movable folding blade arranged 20 below the feeding table, connections between the folding blades and the driving

shaft whereby said blades are reciprocated through intersecting planes at each revolution of the shaft, a rock shaft mounted in the frame and carrying a cutter which aligns with a slot 25 in the feeding table, a printing cylinder adapted to be moved toward and from the feeding table, connections between said cylinder and the rock shaft, and a driving wheel secured on the driving shaft and provided 30 with a laterally projecting pin or stud adapted to contact with an arm attached to the rock shaft, to move both the cutter and the impression cylinder toward the feeding table, substantially as shown and described.

In testimony whereof we affix our signatures in presence of two witnesses.
